UNITED STATES PATENT OFFICE.

BENJAMIN M. SHANKLIN, OF SPRINGFIELD, MASSACHUSETTS.

STRIP-PUNCHING APPARATUS.

1,267,599.

Specification of Letters Patent. Patented May 28, 1918.

Application filed January 15, 1917. Serial No. 142,434.

To all whom it may concern:

Be it known that I, BENJAMIN M. SHANKLIN, a citizen of the United States of America, residing at Springfield, in the county of 5 Hampden and State of Massachusetts, have invented certain new and useful Improvements in Strip-Punching Apparatus, of which the following is a specification.

This invention relates to strip punching apparatus and particularly to apparatus which is arranged to contain and operate upon a roll of transfers in continuous strip form. The invention furthermore relates to an improvement in the punching apparatus disclosed in my co-pending application Serial No. 103,222, filed June 12, 1916.

An object of the invention is to provide in a strip punching apparatus an improved means to position the strip beneath the 10 punching mechanism which means is characterized in that it may operate directly upon the strip itself to positively arrest the latter without injury to the strip.

Another object of the invention is to provide in a strip punching apparatus, punching mechanism involving a plurality of punches adapted for simultaneous actuation, means to arrest the strip when it comes into proper position beneath the punching 15 mechanism, devices operable from said means to positively lock the strip against further movement, and a lever arranged to simultaneously actuate said punches and to release the arresting and locking means to permit an unpunched strip to be positioned beneath the said mechanism.

Another object of the invention is to provide in a strip punching device, a casing, a die plate thereon having a channel to receive 20 the strip, punching mechanism mounted above the channel, means in the rear of said mechanism to support the strip in roll form and a cover to inclose the supporting means, a part of said casing being removable and 25 removably connected to the punching mechanism, the structure being characterized by permitting convenient access to the strip and to the supporting means.

A further object of the invention is to 30 provide in a device of the class described generally improved and simplified mechanical structure for the desired functions.

Other objects and advantages will appear in the following description and in the 35 appended claims.

The invention in a form at present pre-

ferred is shown for illustrative purposes in the accompanying drawings, in which,

Figure 1 is a side elevational view of the 60 punching apparatus;

Fig. 2 is a plan view thereof;

Fig. 3 is a fragmentary sectional elevation taken on the line 3-3 of Fig. 2;

Fig. 4 is an enlarged elevational view 65 with the side wall of the casing broken away to reveal interior mechanism;

Fig. 5 is a cross-sectional view taken on the line 5-5 of Fig. 4;

Figs. 6 and 7 are detail sectional views 70 taken on the lines 6-6 and 7-7, respectively, of Fig. 5;

Fig. 8 is a bottom plan view of the apparatus with the bottom plate removed;

Fig. 9 is a fragmentary sectional view 75 taken on the line 9-9 of Fig. 8;

Fig. 10 is a partial cross sectional view taken on the line 10-10 of Fig. 4; and

Fig. 11 is a cross-sectional view taken on the line 11-11 of Fig. 4.

Referring to these drawings, the improved 80 apparatus comprises, in general, means to receive and support transfers in continuous strip or other convenient form, punching mechanism beneath which the strip may be drawn from said means, devices to automatically position and hold the strip in correct alignment with the punching mechanism and strip releasing mechanism operable only by actuation of the punching mechanism to permit a punched strip to be 85 withdrawn and an unpunched strip to be positioned beneath the punching mechanism.

The general frame structure of the apparatus will first be described with particular 95 reference to Figs. 1, 2, 4, 5, and 8. Reference 15 designates a rectangularly shaped casing which is open from top to bottom. Intermediate the upper and lower edges of the casing are interiorly extending ledges 100 16 (Figs. 5 and 8) and secured to the latter, as indicated in Fig. 8, is a plate 17 which extends from a point adjacent the rear wall of the casing through and beyond the front wall thereof, as shown, in Figs. 1, 2, and 8. 105 The base of casing 15 is closed by a plate 18 removably secured by screws 19 to suitable posts depending from ledges 16, as best shown in Fig. 4. The forward portion of casing 15 is cut away, as shown in Figs. 1, 110 5, and 10, so that its upper edge lies flush with plate 17. A substantially U-shaped

frame 20 (Fig. 2) of the cross-sectional shape shown in Figs. 5 and 10 is adapted to fit in the cut-away portion of casing 15 and is secured to the ledges 16 by screws 21 (Figs. 2 and 10). Frame 20 serves to removably secure the punching mechanism to plate 17 as will appear. The rear upper portion of the casing is closed by a hinged cover 22 which also overlaps a portion of frame 20 to include certain parts of the punching mechanism. Cover 22 is provided with a lock, the cylinder of which is indicated by reference 23 and secured to the inner end of the cylinder (see Fig. 3) is a depending arm 24 which is slotted to engage a pin 25 fixed to an inner wall of casing 15, whereby cover 22 may be locked in an obvious manner.

The punching mechanism is substantially the same as that disclosed in my above-identified copending application and will be herein described only in general terms sufficiently to enable a clear understanding of the invention to be obtained. This mechanism is mounted in three spaced parallel plates 26, 27, and 28 (Figs. 4 and 5), and the upper and lower plates 26 and 28 are fastened by screws, as indicated in Fig. 10, to upright posts 29 which are arranged one at each corner of the plates. The punching mechanism is self-contained and is adapted to fit as a unit within the U-shaped frame 20, as indicated in Figs. 4 and 5. Pins 30 extend outwardly from the sides of lower plate 28 near the rear thereof and engage in suitable slots formed in frame 20, as shown in Fig. 10, so that the punching mechanism may be held to frame 20. The punching mechanism in frame 20 is clamped to plate 17 by the screws 21 described, and, to prevent longitudinal displacement of the mechanism, dowels 31 (Fig. 4) in plate 17 are arranged to fit in suitable recesses in lower plate 28. The intermediate plate 27 is slidable on a central post 32 (Fig. 5) secured to and extending between the upper and lower plates. Springs 33 normally hold plate 27 in raised position as illustrated. Slidably mounted in lower plate 28 are a plurality of punches 35 normally held retracted by springs, as shown in Fig. 9. Suitable holes 36 are formed in plate 17 in alignment with these punches. The latter, as disclosed in the above-identified application, are arranged in groups with movable selectors, whereby any desired punch of a group may be connected for actuation by plate 27. For example, in Figs. 1 and 2 are selectors 37, 38, 39, and 40 which may control the month, day, hour, and minute group of punches, and 41 a selector which controls the "A. M." or "P. M." printed designation on the transfer strip. The selector 38 is shown in Fig. 9, and, for the present purposes, it will suffice to state that it may be

moved to overlie any desired punch of its group and has a part 41 engageable by the intermediate plate 27 to depress the selected punch. For a more detailed disclosure of the selectors, reference is made to the above-identified application. Other punches 42 indicate those punches, for example, as are adapted to punch the "destination" designations on the transfer strip, and those are mounted in the plates 26, 27, and 28, as shown in Figs. 4 and 5, and are arranged for manual operation independently of the depression of plate 27, suitable holes 43 being formed in plate 17 (Fig. 8) to align with these punches. It is to be noted that the month and day selectors 37 and 38 are included within cover 22 and, therefore, rendered inaccessible except to authorized persons.

The mechanism for depressing the intermediate plate 27 to simultaneously actuate the selected punches of the several groups will now be described with particular reference to Figs. 4 to 8, inclusive. A U-shaped plate 45 is set into the intermediate plate 27 centrally on each side thereof and is secured thereto by screws, as indicated in Figs. 4 and 5. Secured to the outer face on each side of lower plate 28 are brackets 46, and frame 20 is suitably recessed, as shown in Figs. 5 and 8, to receive the brackets. Referring to Fig. 4, the described pins 30 are located near the rear end of plate 28 and the frame 20 has been recessed, as best shown in Fig. 8, so that the frame and plate 20 can be moved, the one relatively to the other to withdraw pins 30 from their slots. A pin 47 is riveted to the bracket 46 and extends inwardly therefrom (Fig. 5). Loosely mounted on each pin 47 is a ratchet 48 and gear 49 which, as shown in Fig. 5, are pinned together. A wheel 50 is also loosely mounted on each pin 47 and is provided with a spring pressed pawl 51 (Fig. 7) to engage the teeth of ratchet 48.

Referring to Fig. 6, each wheel 50 has formed on its inner face a suitable cam 52 which extends into the U-shaped piece 45 and is adapted to engage the cross piece of the latter to depress the intermediate plate when the wheel is rotated. Cam 52 may advantageously be formed in the shape of a modified equilateral triangle as shown. Horizontally slidable in guides formed in bracket 46 is a rack 53 which engages gear 49. Rack 53 is reciprocable by means to be described and, when moved in the direction of the arrow (Figs. 6 and 7), the wheel 50 will be turned by reason of the engagement of pawl 51 with ratchet 48. When moved in the opposite direction, the teeth of the ratchet snap freely by the pawl without turning the wheel. The racks 53 are given just sufficient movement to turn cams 52 through an angle of 120 degrees, so that

cam, starting from the position shown in Fig. 6, depress plate 27 and thereafter are carried into a position similar to the starting position, whereby plate 27 is free to rise. Thus, by pulling rack 53 rearwardly, plate 27 will be lowered, the members 45 passing freely through notches formed in plates 17 and 28, as shown in Figs. 5 and 8, and the return of plate 27 is effected by the 10 springs 38 described.

The racks 53 extend rearwardly beyond the punching mechanism (Fig. 4) and have a pin and slot connection with crank arms 55. The latter are integrally formed on a 15 shaft 56 pivoted at 57 to the walls of casing 15 and extending therebetween below plate 17. A crank 58 centrally formed on shaft 56 is connected by a link 59 to a lever 60 pivoted at 61 to and between spaced ears 20 formed on the rear wall of casing 15. Springs 62 arranged on each side of link 59 (Fig. 8) normally hold crank arms 55 in the position shown. The upper face of link 59 has a slot 63 (Fig. 8) formed therein adjacent plate 17, and a pin 64 on the latter rides in the slot whereby the movement of link 59 is limited in both directions. The lever 60, as shown in Figs. 1 and 2, extends above cover 22 and is bent forwardly thereover so 25 that it may be conveniently engaged by the operator. The pivot 61 is made conveniently removable so that the lever 60 may be swung backwardly on its pivotal connection with link 59 to permit cover 22 to be opened, 30 On a depression of the forward end of lever 60 both racks 53 are simultaneously drawn back to effect an equal turning movement of the cams 52 whereby plate 27 is uniformly lowered to actuate the several selected 35 punches.

The supporting devices for the transfer roll will next be described with particular reference to Figs. 4 and 11. The transfers in continuous strip form are wound upon a 45 core 65 the transfer strip being indicated by reference 66. The core 65 is rotatably supported at its ends by a pair of studs 67 and 68 which enter openings in the end of the core, as shown in Fig. 11. Stud 67 is 50 riveted to an upstanding arm of a bracket 69 secured to plate 17, and stud 68 is fixed in the upper end of a bent arm 70 pivoted at 71 to bracket 69. The arm 70 may be swung outwardly, when desired, to withdraw stud 68, whereby the core 65 and transfer roll thereon may be conveniently removed. A leaf spring 72, bent as shown in Fig. 11, is secured at one end to arm 70, and its free end engages the side wall of casing 55 to normally hold stud 68 in engagement with the core. The plate 17, heretofore described, is provided in its upper face with a channel 73 through which the transfer strip 66 may be passed. Channel 73 extends from 60 the forward end of plate 17 rearwardly to a

position closely adjacent bracket 69, as best shown in Fig. 9. A guide 74 secured to plate 17 bridges channel 73 and has its rear end rounded and upturned, as shown in Fig. 9, to form an entrance for strip 66. The latter 70 passes beneath the guide 74 and forwardly beneath plate 28 of the punching mechanism to the forward edge of plate 17.

The means for positioning the transfer strip properly beneath the punching mechanism and for locking the strip against withdrawal will now be described with reference to Figs. 4, 8, and 9. The transfer strip, as disclosed in the above-identified copending application, is perforated transversely at 80 suitable intervals to provide for convenient severing of the strip into unit transfers and adjacent each line of perforations, a hole is formed centrally in the strip for co-operative engagement with the positioning devices. 85 The length of each transfer unit is substantially equal to the distance from the forward edge of guide 74 to the forward edge of plate 17 so that the hole in the strip lies closely adjacent the guide as shown in Fig. 9, reference 75 designating the hole in the transfer strip. A rod 76 having a beveled upper end is adapted to enter (in a manner later to be described in detail) hole 75, as shown in Figs. 8 and 9, when strip 66 is 90 properly positioned beneath the punching mechanism so that the appropriate printed designations on the transfer strip are aligned beneath the proper punches 35. The lower end of rod 76 is bifurcated and is pivoted 100 to an arm 77 by a stud 78, the latter turning with the rod. A spring 79 fixed at one end to arm 77 is connected to stud 78 in such a manner that rod 76 is constantly forced rearwardly, and, when positioned as shown in 105 Fig. 9, abuts the forward end of the paper guide 74. The hub of arm 77 is pivotally supported in a bracket 80 (Figs. 4 and 8) fixed to plate 17 and from this hub a second and shorter arm 81 extends at substantially 110 right angles to arm 77.

A positive locking means is provided for the transfer strip to prevent rotation of the transfer roll. Referring to Figs. 4 and 11, a ratchet 82 is loosely mounted on the core 115 supporting stud 67 and is restrained from axial movement by a set screw 83 which rides in a groove in stud 67. Ratchet 82 has projections 84 on either side of stud 67 which enter a slot in the end of the core 65, as 120 shown in Fig. 11. Thus, the ratchet and core are removably coupled in an operable driving engagement. A pawl 85 pivoted to a bracket 86 fixed to plate 17 is adapted normally to engage the teeth of ratchet 82 by 125 reason of a spring 87 connected to the pawl and to the bracket 69, as shown in Fig. 4.

The means for releasing the ratchet 82 and the positioning rod 76 will now be described with reference to Figs. 4, 8, and 9. 13

The arm 81 and pawl 85 are connected by adjustable connecting rods 88 and 88', respectively, to an arm 89 of a bell crank pivoted at 90 to a bracket 91 secured to plate 17. The other arm 92 of the bell crank extends forwardly and substantially horizontally to a position adjacent the rear of the punching mechanism. A plate 93 fastened to the upper face of the intermediate plate 27 directly overlies the end of arm 92 so that, as plate 27 is depressed by the described mechanism, the bell crank lever is rocked to remove pawl 85 from engagement with its ratchet and to retract the positioning rod 76 in an obvious manner. As the rod 76 is withdrawn, it is thrown rearwardly by spring 79 as far as permitted by the limits of the slot in plate 17 in which the rod is movable and a guard pin 94 is riveted to plate 17 adjacent the rear end of this slot as a precautionary measure in case the rod should be moved slightly below plate 17. The rod 76 is immediately thrown upwardly as soon as the lever 60 is released by the force of spring 87, but this upward movement is limited by engagement of the rod with the portion of transfer strip 66 behind the hole 75 so that the pawl 85 is held out of engagement until the rod enters a succeeding hole 75 in the transfer strip. The forward central portion of the guide 74 is upturned as indicated at 95 so that the central part of strip 66 is thrown upwardly which, together with the beveled edge of rod 76, facilitates entrance of the latter into a succeeding hole 75 in the transfer strip.

A device is provided to indicate when the punching mechanism has operated. This device in the embodiment illustrated takes the form of a bell 96 (Figs. 4, 5, and 8) which is secured to the plate 17 and depends into the "chip" chamber formed between the latter and bottom plate 18. A hammer lever 97 is pivoted to plate 17 at 98 and has a lug 99 (Figs. 5 and 8) which lies in the path of a pin 100 fixed in the crank shaft 56 heretofore described. A spring 101 normally holds lever 97 retracted with the striking end thereof against a suitable buffer 102 on the side of casing 15 (Figs. 5 and 8). As crank shaft 56 is rocked, pin 100 engages lug 99 and swings the lever sharply against the gong 96, thereby indicating that the mechanism has been operated and the transfer strip may be withdrawn. The indicator is also desirable for the usual reasons as a check on the operator.

The operation of the apparatus will now be described. Assuming that the transfer strip 60 is positioned as shown in the drawings and that the operator has moved the selectors 37, 38, 39, 40, and 41 to overlie the desired punch of each group, the desired destination punch 42 is then depressed and thereafter lever 60 is actuated. A depression of

the latter will pull the racks 53 rearwardly in unison and turn cams 52 so that plate 27 will be uniformly lowered to simultaneously actuate the several selected punches. The return movement of racks 53 will turn the gears 49 idly without moving the cams, due to the pawl 51 and ratchet 48. As plate 27 is lowered, the arm 92 is depressed which removes pawl 85 from engagement with its ratchet and withdraws the member 76 from the perforation 75 in the transfer strip. Immediately as the member 76 is withdrawn, it is forced rearwardly by spring 79 so that, when lever 60 is released and the member 76 moves upwardly, the latter will engage the strip in back of its former position. With this arrangement, the strip is backed up by guide 74 so that it cannot be injured by the engagement of the member 76. It is also to be noted that the guide 74 so limits the upward movement of member 76 that the pawl 85 is held out of engagement with ratchet 82. The strip 66 may, therefore, be drawn forwardly to permit removal of the punched transfer and to bring an unpunched transfer beneath the punching mechanism. As the strip is moved forwardly, a succeeding perforation 75 eventually engages the beveled end of the member 76, and further movement of the strip will move the member forwardly against the tension of spring 79. As soon as the perforation completely passes beyond guide 74, the member 76 will immediately be forced upwardly by reason of spring 87, and pawl 85 will be simultaneously caused to engage its ratchet to positively prevent further movement of the strip. This particular construction of the member 76 and associated parts is important since it permits control of the strip through direct engagement therewith and without any possibility of injury to the strip. The gong 96 is sounded when lever 60 is depressed and indicates that the strip is released ready for withdrawal. It is to be noted that pin 100 does not immediately engage the lug 99 of the gong lever when lever 60 is actuated, but the engagement occurs during the last part of the movement of the lever 60 so that the gong 96 is not sounded until the strip 66 is completely released.

To insert a new roll of transfers, the stud 61 is removed and lever 60 swung rearwardly. Thereafter, cover 22 is unlocked and raised whereby complete access is had to the roll supporting devices. Arm 70 is then swung outwardly, the core 65 removed and the new roll inserted in place. By removing the frame 20, the punching mechanism is also removed, the racks 53 lifting readily from the pins in arms 55. The strip may then be led forwardly in channel 73 and properly positioned after which the frame 20 and punching mech-

anism is replaced. If, for any reason, access to the punching mechanism is desired, it may be removed by sliding it relatively to the frame 20 to withdraw pins 30 from the slots in the latter. After the strip has been positioned as described, the cover 22 is closed and locked, and stud 61 is replaced so that the normal operation may be resumed.

10 It is to be noted particularly that the month and day selectors 37 and 38 are locked within cover 22 and are inaccessible to the operator so that "dating ahead" of transfers is prevented. Moreover, no transfers

15 can be removed from the apparatus until they have been punched since the strip releasing means is operable only by actuation of the punching mechanism. The gong 86 gives a clear signal on the issuance of each

20 transfer and, if desired, arm 97 may be made to operate a register to count the transfers issued.

The invention has been described in a preferred form for illustrative purposes, but the scope of the invention is defined by the appended claims rather than by the foregoing description.

What I claim is—

1. In a strip punching device, a casing having means to receive the strip and a passage through which the latter may be passed, a separately operable punching mechanism mounted adjacent said passage, and means operable independently of said mechanism to arrest the strip when it becomes properly positioned relatively to said mechanism and to lock the strip in such position until it is punched.

2. A strip punching device, comprising, a casing having means to receive the strip and a passage through which the latter may be passed, punching mechanism mounted adjacent said passage, devices to lock the strip when a portion thereof comes into proper position relatively to the punching mechanism, and means to release said devices when the strip is punched and to hold said devices released until a succeeding portion of the strip becomes properly positioned relatively to the punching mechanism.

3. In a strip punching device, a punching mechanism, relatively powerful means to actuate and restore the latter, a relatively delicate positioning and locking mechanism operable by direct engagement with the strip to properly position the latter with relation to the punching mechanism and to lock the strip when thus positioned, means independent of the punching mechanism to actuate the positioning and locking mechanism, and means controlled by the punching mechanism to reset the last-named mechanism for a subsequent cycle of locking operation with each actua-

tion of the punching mechanism, all constructed and arranged for the control of the delicate mechanism by the powerful means without injury to the strip.

4. In a strip punching device, a punching mechanism, means to actuate the latter, relatively heavy devices to restore the mechanism to normal position after the operation of said means, a positioning and locking means for the strip operable to arrest the latter when it comes into proper position with relation to said mechanism and to lock the strip until actuation of the mechanism, relatively light devices tending to throw the last-named means into locking position, means operable by actuation of said mechanism to release the locking and positioning means, and means controlled by engagement with the strip to hold the locking and positioning means released until a succeeding portion of the strip becomes properly positioned with relation to the punching mechanism, all constructed and arranged so that the positioning and locking means is controlled by the punching mechanism but is released from the action of the relatively heavy restoring devices to prevent injury to the strip.

5. A strip punching device, comprising, in combination, a casing having means at one end to receive the strip in roll form and a channel extending to the other end thereof through which the strip may be drawn, punching mechanism mounted adjacent the channel leaving the forward end exposed whereby the strip may be pulled through the channel, a guiding member mounted adjacent the channel and punching mechanism and means to arrest the strip when it comes into proper alinement with the punching mechanism, said means comprising a device pivoted for swinging movement toward the strip and member and pivoted for swinging movement in the line of travel of the strip, said device arranged to bear against the strip while the latter is backed up by said guiding member, all constructed and arranged so that as the strip is drawn through the channel a perforation therein is engaged by said device and the latter is drawn forwardly beyond said member so that the device may pass through the perforation to position the strip.

6. A strip punching device, comprising in combination, a casing having means at one end to receive the strip in roll form and a channel extending to the other end thereof through which the strip may be drawn, punching mechanism mounted adjacent said channel leaving the forward end exposed, whereby the strip may be pulled through the channel, means engageable with the strip to arrest the latter when it comes into proper alinement with said mechanism, means operable by the actuation of the ar-

resting means to lock the first-named means against further movement, means to actuate the punching mechanism, and devices operable by actuation of the latter to release the strip from engagement with the arresting and locking means to permit the punched strip to be withdrawn.

7. A strip punching device, comprising in combination, a casing having means at one end to receive the strip in roll form and a channel extending to the other end thereof through which the strip may be drawn, punching mechanism mounted adjacent said channel leaving the forward end exposed, whereby the strip may be pulled through the channel, means engageable with the strip to arrest the latter when it comes into proper alignment with said mechanism, means operable by the actuation of the arresting means to positively lock the first-named means against further movement, means to actuate the punching mechanism and devices operable by actuation of the latter to release the strip from engagement with the arresting and locking means to permit the punched strip to be withdrawn, said arresting and locking means constructed and arranged to release the strip until a succeeding portion thereof becomes properly positioned beneath the punching mechanism.

8. In a strip punching device, a casing, a punching mechanism in the casing, said mechanism comprising parallel plates, one thereof being depressible, punches mounted in one of said plates and means on the depressible plate to actuate the punches when the plate is depressed, cams rotatably supported from one of the plates and adapted to engage the sides of the other plate substantially in the center thereof, a lever pivoted to the casing and reciprocable means in the latter operable by said lever to rotate the cams in unison to uniformly lower the depressible plate.

9. In a strip punching device, a casing, a punch carrying plate, punches therein, a depressible plate having means to engage and actuate said punches, cams rotatably supported from one of the plates and adapted to engage the sides of the other plate to lower the latter, a gear for each cam, a ratchet and pawl connection between each gear and cam, racks slidable in the casing and in mesh with the gears, a lever pivoted to the casing and means operable therefrom to reciprocate the racks in unison, all constructed and arranged so that movement of the racks in one direction will rotate the cams to lower the plate and so that the racks may move in the other direction without turning the cams.

10. A strip punching device, comprising, a casing having means at one end to receive the strip in roll form, and a channel extend-

ing to the other end thereof through which the strip may pass, punching mechanism mounted adjacent the channel leaving the forward end exposed whereby the strip may be pulled through the channel, a guide mounted adjacent the channel in the rear of said mechanism, and means to arrest the strip when it comes into proper position relatively to the punching mechanism, said last-named means comprising a pivoted lever, means tending to swing the latter toward the strip, a member pivoted to the end of the lever and resilient means connecting the lever and member, all constructed and arranged so that the member bears against the strip while it is backed up by said guide and so that, as the strip is drawn forwardly, a perforation therein engages said member and moves the latter forwardly of the guide so that the member may pass through the perforation.

11. A strip punching device, comprising, a casing having means at one end to receive the strip in roll form, and a channel extending to the other end thereof through which the strip may pass, punching mechanism mounted adjacent the channel leaving the forward end exposed whereby the strip may be pulled through the channel, a guide mounted adjacent the channel in the rear of said mechanism, means to arrest the strip when it comes into proper position relatively to the punching mechanism, said last-named means comprising a pivoted lever, means tending to swing the latter toward the strip, a member pivoted to the end of the lever and resilient means connecting the lever and member, all constructed and arranged so that the member bears against the strip, while it is backed up by said guide and so that, as the strip is drawn forwardly a perforation therein engages said member and moves the latter forwardly of the guide so that the member may pass through the perforation, and devices operable by the lever when the member passes through the perforation to lock the strip against further movement.

12. A strip punching apparatus comprising in combination, a casing having means at one end to support the strip in roll form and a channel extending to the other end thereof through which the strip may pass, punching mechanism mounted adjacent the channel leaving the forward end exposed whereby the strip may be pulled through said channel, means directly and yieldingly engageable with the strip to arrest the latter when it comes into proper position beneath the punching mechanism, and means operable by the arresting means to lock the strip against further movement.

13. In a strip punching device, a casing open from top to bottom, a die plate secured to the casing to partition the latter, the forward portion of the casing being separable

along the plane of the die plate, a punching mechanism removably secured to said separable portion, a removable bottom closure for the casing, means in the latter and in the

- 5 rear of said mechanism to support the strip in roll form, a channel in the upper face of the die plate through which the strip may pass, and a pivoted cover to close the rear portion of the casing, and to overlie a part 10 of the punching mechanism, all constructed and arranged so that said cover and mechanism may be conveniently removed to expose the strip and said means.

14. In a strip punching device, a casing, a 15 supporting member removably mounted therein, supporting, guiding, positioning, and locking devices for the strip, all mounted on said member, a unitary self-contained 20 punching mechanism including punch operating devices, all constructed and arranged so that the first-named devices may be conveniently assembled on said member and positioned as a unit within the casing and so 25 that the punching mechanism may be separately assembled and applied to said member as a unit and means in the casing to actuate the operating devices, the latter and said means being removably connected to permit ready removal and replacement of 30 the punching mechanism when desired.

15. In a strip punching device, a casing, a 35 supporting member removably mounted therein, supporting, guiding, positioning, and locking devices for the strip, all mounted on said member, and a unitary self-contained 40 punching mechanism removably mounted on said member, all constructed and arranged so that said devices may be conveniently assembled on said member and the latter with the devices thereon may be positioned as a unit within the casing and

so that the punching mechanism may be separately assembled and applied to said member as a unit.

16. In a strip punching device, a casing 45 having means to receive the strip, a punching mechanism including punch operating devices mounted in the casing, the latter having a part co-operating with said mechanism to afford a continuous slot adjacent the latter through which the strip from said means may pass with its edges and both faces confined, a device adapted to engage in a perforation in the strip to lock the latter when it comes into proper position relatively to 50 the punching mechanism, and means independent of the punching mechanism to yieldingly force said device against the strip.

17. In a device of the class described, a casing having a channel through which a 60 strip may pass, mechanism mounted adjacent the channel to operate on the strip therein, a guiding member to confine the strip in the channel, and means to automatically lock the strip when it comes into 65 a predetermined position in the channel, said means comprising a part yieldingly bearing against the strip while the latter is backed up by said guide and arranged to engage a perforation in the strip, said part 70 being movable by the strip to carry the former beyond said member and into strip locking position, and resilient means tending to restrain movement of said part by the strip, whereby when said part is withdrawn 75 from the perforation the last-named means may move it away from the perforation and out of strip locking position, and means controlled by the operation of said mechanism to withdraw said part.

BENJAMIN M. SHANKLIN.
